United States Patent Office.

WILLIAM N. WHITELEY, OF SPRINGFIELD, OHIO.

Letters Patent No. 81,044, dated August 11, 1868.

IMPROVEMENT IN HARVESTER-CUTTERS.

The Schedule referred to in these Letters Patent and making part of the same.

TO ALL WHOM IT MAY CONCERN:

Be it known that I, WILLIAM N. WHITELEY, of Springfield, in the county of Clark, and State of Ohio, have invented a new and useful Improvement in Pitman-Connections, &c., for Harvesters' Cutting-Apparatus; and I do hereby declare the following to be a full, clear, and exact description of the same, reference being had to the accompanying drawings, in which—

Figure 1 is a plan view of the pitman detached.

Figure 2 is a plan view of the pitman and a part of the cutter-bar.

Figure 3 is a bottom plan of the tightening-nut.

That others may understand this construction and operation, I will particularly describe it.

A is the pitman, made forked at its lower end, so as to enclose the heel of the cutter-bar between its two parts B B, as shown in fig. 2. These two branches may be attached to the main rod of the pitman in any convenient way, by forging, welding, or by rivets or screws. The pivots, forming the joint between the pitman A and the cutter-bar E, are made in the form of conical, conoidal, or spherical lugs, C C, projecting into seats or cavities of corresponding form and size. These lugs may project from the heel of the cutter-bar E into seats made in the inner surfaces of the branches B B, or they may project from said branches into seats formed in the heel of the cutter-bar. The latter mode of construction is shown in the drawings.

The advantage of a joint of the construction is well known. It admits of being maintained in proper, snug working-order constantly, without slack or lost motion, and thereby is made much less noisy and much more durable. But it is evident that this result cannot be attained unless some device is employed to retain the branches B at a fixed relative distance, and to permit their ready adjustment at the proper distance. The bolt F, with a screw-nut, has hitherto been employed for this purpose, but it has been found that the violent movement of a harvester's pitman would cause the nut to work back upon the bolt and loosen the joint, and that said nut would frequently work entirely off the bolt. To obviate this danger, the nut has been made with a ratchet on its edge, and a spring-pawl or stop secured to the outside of the pitman, with its free end engaging with said ratchet.

The position of a spring-pawl on the outside of the pitman renders it constantly liable to derangement and displacement by accumulations of clogging matter or accidental contact with foreign substances. I have, therefore, placed the ratchet on the bottom or under surface of my nut G, as shown in the drawings, and the spring-stop H, I place between the branches B B, and project its free end through an orifice made for that purpose in one of the branches. The spring-stop H may be in the form of a flat spring, as shown in fig. 1, or it may be a spiral spring, as in fig. 2, coiled around the bolt F. In the latter form it will be not only very cheap, but it will also be less liable to derangement and injury than when made in any other form. I, however, do not wish to limit myself to any particular form of stop further than the limitation of its position. The shank of the bolt F, near its head, must be made square, or otherwise prevented from turning in its hole, as any rotary movement on its axis would necessarily impair the action of the spring-stop and ratchet-nut.

The spiral spring coiled about the bolt F may perform the double function of pressing the branches asunder, so as to insure their constant pressure against the lower face of the nut, and engaging with the ratchet of said nut to hold it in place.

When the joint of the cutter-bar and pitman is made in line with the cutter-bar, it is not in the line of action and resistance of the cutter, because that line will be about midway from the points to the heel of the cutter, and there will therefore be more or less side draught to the cutters, resulting in an increase of friction on the cutter-bar, and a greater consumption of power. The position of the line of draught will never be exactly midway between the front and heel of the cutters, but some distance in rear of said position, because the friction of the cutter-bar in its glide-way will be a constant resistance, counterbalancing, more or less, the resistance of the grass against the cutters, and their effects do not depend at all upon the construction of the joint between the cutter-bar and pitman. I have, therefore, curved the heel of my cutter-bar E sideways, as shown

in fig. 2, so as to bring the pitman-joint as nearly as possible into the real line of draught. The actual position of the line of draught will be subject to constant variation, because the resistance experienced by the cutters will constantly vary as the grass is thick or thin.

Having described my invention, what I claim as new, is—

1. The cutter-bar E, bent forward at its inner end, substantially as and for the purpose set forth.
2. A spring, located between the branches of the pitman, and with one of its ends extending through one of said branches so as to engage with the ratchet of the nut G, substantially as set forth.
3. A spring, located between the branches of the pitman, and shaped and secured so as to press the said branches asunder, and at the same time penetrate through the proper hole in one of said branches, and engage with the ratchet of the nut G, substantially as set forth.

WM. N. WHITELEY.
